Specification for Design.

Patented Aug. 1, 1911.

Application filed February 2, 1911. Serial No. 606,263. Term of patent 14 years.

To all whom it may concern:

Be it known that I, WILLIAM L. BELKNAP, a citizen of the United States, residing at Bridgeport, in the county of Fairfield and State of Connecticut, have invented a certain new, original, and ornamental Design for a Valve-Body; and I do hereby declare the following to be a full, clear, and exact description of the design, such as will enable others skilled in the art to which it appertains to make and use the same, reference being had to the accompanying drawings, forming a part thereof.

Figure 1 is a perspective view; and Fig. 2 is a side elevation of a valve body showing my new design.

I claim:

The ornamental design for a valve body as shown.

WILLIAM L. BELKNAP.
